ROTARY FLUID-PRESSURE MOTOR.

1,077,568.

Specification of Letters Patent.

Patented Nov. 4, 1913.

Application filed February 18, 1913. Serial No. 749,182.

To all whom it may concern:

Be it known that we, WILLIAM F. SULLIVAN, a citizen of the United States, and ALFRED M. WASBAUER, a citizen of France, residing at Paterson, in the county of Passaic and State of New Jersey, have invented certain new and useful Improvements in Rotary Fluid-Pressure Motors, of which the following is a specification.

10 The motor which is the subject of the present invention is designed more particularly for operating a steering gear, a rotor being provided which makes less than a complete revolution and then automatically 15 stops, the extent of travel of the rotor being controlled by a valve and an arrangement of ports in the rotor as will be hereinafter described in detail and claimed. Provision is also made for connecting the 20 motor to the parts to be operated.

In order that the invention may be fully understood, reference is had to the accompanying drawings, in which—

Figure 1 is an elevation of the motor with 25 one of the cylinder heads removed. Fig. 2 is a vertical section on the line 2—2 of Fig. 1. Fig. 3 is a horizontal section on the line 3—3 of Fig. 1. Fig. 4 is a view similar to Fig. 1 showing the controlling valve shifted 30 to admit fluid pressure into the cylinder to rotate the rotor counterclockwise. Fig. 5 is a face view of the controlling valve. Fig. 6 is a view similar to Fig. 1 showing a modification. Fig. 7 is a vertical section on the 35 line 7—7 of Fig. 6. Fig. 8 is a face view of the controlling valve shown in Figs. 6 and 7. Fig. 9 is a face view of another modified form of controlling valve.

In the drawings 10 denotes a cylinder 40 which incloses a rotor 11, having radially projecting piston wings 12. The cylinder is divided into three chambers 13 in which the piston wings work, each chamber containing one piston wing. It will be understood, of course, that the number of piston wings and corresponding chambers may be varied according to the work for which the motor is designed. The chambers are formed by abutments 14 extending radially 45 between the cylinder wall and the periphery of the rotor, the inner ends of the abutments being provided with grooves for a packing 15, in order to prevent the fluid pressure from escaping between the chambers. The 50 outer ends of the piston wings are also pro-

vided with a packing 16 so that a fluid tight joint is had between the same and the cylinder wall. The rotor and the piston wings extend entirely across the space between heads 17 and 18 closing the respective 60 ends of the cylinder, and the ends of the wings are provided with a packing 19. The ends of the rotor have annular grooves to receive a packing 20. The packings 19 and 20 are provided to prevent escape of 65 the fluid pressure between the ends of the rotor and wings, and the cylinder heads.

That end of the rotor 11, which is next to the cylinder head 17, has a hub extension 21 passing through a central opening in 70 said head. The hub extension has a central hollow which is continued through the center of the rotor to the opposite end thereof. In this hollow is mounted a hollow valve stem 22 which projects at one end from the 75 hub extension and has on the outside thereof side openings or ports 23, establishing communication between the hollow 23^a of the stem and the external atmosphere, and serving as exhaust outlet ports as will 80 be presently described. The other end of the valve stem has a collar 24 which is countersunk in the corresponding end of the rotor, and carries pins 25 designed to enter holes in a rotary valve 26, which seats 85 against said end of the rotor, said pins thus serving to provide a driving connection between the stem and the valve. This driving connection prevents the stem from binding 90 the valve and the latter from resting unevenly on its seat. The cylinder head 18 has a recess 27 to accommodate the valve and forms an inlet chamber having a suitable supply connection 28.

The valve 26 is a circular disk having an 95 outstanding marginal flange 29 on the side which seats on the end of the rotor 11. On the same side of the disk are three partitions 30 which extend inward from the marginal flange and form with the latter three chambers 31, which are spaced from each other. The space inclosed by the walls of the chambers forms an exhaust cavity 32, the same being located at the center of the disk and having three radially extending 100 branches or passages 33. The exhaust cavity 32 opens to the hollow 23^a of the valve stem, the same forming an exhaust passage, the outlet of which is through the ports 23.

In the valve disk 26 are admission ports 34 110

extending entirely therethrough from one side to the other. Three pairs of admission ports are provided corresponding to the number of piston wings 12 and chambers 13.

5 The ports open at one end into the inlet chamber 27, and at their other ends the pairs of ports open respectively into the chambers 31 adjacent to the partitions 30.

In the end of the rotor 11 on which the 10 valve 26 seats are inlet ports 35, the inner ends of which are deflected so as to open through the periphery of the rotor into the chambers 13. These ports are located the same radial distance from the center of the 15 rotor as the ports 34, and are therefore adapted to be lapped by the latter. Three pairs of ports 35 are provided, one pair for each chamber 13, and the members of said pair opening into the chamber on opposite 20 sides of the piston wing 12.

The ports 35 are so positioned with respect to the ports 34, that when the rotor 11 is at rest, the ports 34 slightly lap the ports 35. Pressure is therefore admitted into the 25 chambers 13 on both sides of the piston wings 12, and the latter are thus balanced and held stationary. At the same time the exhaust cavity 32 and its branches 33 are covered by the end of the rotor, said 30 branches lying between the right and left ones of the members of the respective pairs of ports 34. If now the valve 26 is turned to the left, pressure is admitted into the chambers 13 to the right of each piston wing 12 and the rotor is caused to move counter-clockwise, or in the same direction the valve was moved, thus following the valve and stopping wherever the valve has stopped. At the same time the valve is moved to the 40 left to admit pressure into the chambers 13 to the right of the piston wings 12, the left hand admission ports 34 are closed and the exhaust passages 33 come over the ports 35 to the left of the piston wings. The pressure in the chambers 13 to the left of the piston wings then escapes through the passages 33 into the cavity 32, and thence escapes into the passage 23^a and finally exhausts through the ports 23.

45 50 It will be seen from the foregoing that when the valve 26 is moved to the left, the three ports 35, to the right of the piston wings 12, become intake ports and the other three ports 35, to the left of the piston wings, become exhaust ports. When the valve is moved to the right the reverse action takes place. When the motor is at rest, equal pressure is admitted into all chambers 13 of the cylinder. It will also be understood that the cylinder 10 can be made with one chamber or with any number, according to the work required of the motor. In the present instance the rotor will have a movement equivalent to substantially 90°, and by providing three chambers and a cor-

responding number of pistons, the whole motor is reduced in size since there is obtained three times the power which would be obtained were the cylinder made with but one chamber.

70 The motor is designed primarily for operating a steering gear, although not limited to such use, a suitable driving connection being provided which can be connected to the hub extension 21. No packing is required where the hub extension passes through the cylinder head 17. The valve 26 is designed to be operated by hand, a suitable operating device being connected to the projecting portion of the valve stem 22.

75 The structure herein described produces a simple, efficient and powerful motor which automatically stops after having rotated a predetermined distance.

80 The preferred embodiment of the invention has been shown but it will be evident that various changes in the structure may be made without a departure from the spirit and scope of the invention as hereinafter claimed.

85 Figs. 6 and 7 show a rotor 36 having one piston wing 37, and an end recess 38 in which the controlling valve 39 seats. By thus recessing the end of the rotor and seating the valve in the recess, there is a saving 90 in space. The controlling valve has a single radial portion 40 provided with an exhaust cavity 41 similar to the exhaust cavity 33 of the first described valve, and in the center of the valve is an exhaust cavity 42 95 which is in communication with the cavity 41 and corresponds to the exhaust cavity 32 of the first described valve. The diameter of the end recess 38 in which the valve 39 seats is equal to the diameter of said valve plus its extension 40. Thus a portion of the recess is unoccupied by the valve and through this space the pressure is admitted.

100 Fig. 9 shows a controlling valve 43 similar to the last described valve 39 designed 105 for a rotor having three piston wings similar to the first described structure. In this case the valve has three radial extensions 44 corresponding to the extensions 40.

110 Both of the two last described controlling valves operate in the same manner as the first described valve.

I claim:

1. A rotary fluid pressure motor comprising an inclosing chamber, a rotor having a radial piston wing working in the chamber, and end ports opening into the chamber on opposite sides of the piston wing, a rotatable valve seating on the ported end of the rotor, said valve normally uncovering both end ports of the rotor, and also provided with an exhaust passage, and an inlet chamber in which the valve is located.

120 125 130 2. A rotary fluid pressure motor comprising an inclosing chamber, a rotor having a

- radial piston wing working in the chamber, and end ports opening into the chamber on opposite sides of the piston wing, a rotatable valve seating on the ported end of the 5 rotor, said valve normally uncovering both end ports of the rotor, and also provided with an exhaust passage, an inlet chamber in which the valve is located, and an operating stem connected to the valve, said stem 10 passing through the center of the rotor and being provided with an exhaust outlet in communication with the exhaust passage of the valve. 3. A rotary fluid pressure motor comprising an inclosing chamber, a rotor having a hub extension at one end projecting from the chamber, a radial piston wing carried by the rotor and working in the chamber, said rotor also having end ports opening into the 20 chamber on opposite sides of the piston wing, a rotatable valve seating on the ported end of the rotor, said valve normally uncovering both end ports of the rotor, and also provided with an exhaust passage, and 25 an inlet chamber in which the valve is located. 4. A rotary fluid pressure motor comprising an inclosing chamber, a rotor having a hub extension at one end projecting from the chamber, a radial piston wing carried by the rotor and working in the chamber, said rotor also having end ports opening into the chamber on opposite sides of the piston wing, a rotatable valve seating on 35 the ported end of the rotor, said valve normally uncovering both end ports of the rotor, and also provided with an exhaust passage, an inlet chamber in which the valve is located, and an operating stem connected 40 to the valve, said stem passing through the rotor and the hub extension and projecting from the latter, and having an exhaust outlet in communication with the exhaust passage of the valve. 45 5. A rotary fluid pressure motor comprising a cylinder, radial abutments in the cylinder, a rotor in the cylinder and having radial piston wings working in the cylinder space between the abutments, said rotor also 50 having end ports opening into the cylinder space on opposite sides of the pistons, a rotatable valve seating on the ported end of the rotor, said valve normally uncovering respectively the end ports of the rotor, and 55 also provided with exhaust passages, and an inlet chamber in which the valve is located. 6. A rotary fluid pressure motor comprising a cylinder, heads closing the ends thereof, one of said heads having an inlet chamber, radial abutments in the cylinder, a rotor in the cylinder and having radial piston wings working in the cylinder space between the abutments, said rotor also having end ports opening into the cylinder space on opposite sides of the piston wings, and a rotatable valve located in the aforesaid inlet chamber and seating on the ported end of the rotor, said valve normally uncovering respectively the end ports of the rotor, and also provided with exhaust passages. 7. A rotary fluid pressure motor comprising a cylinder, heads closing the ends thereof, radial abutments in the cylinder, a rotor in the cylinder and having radial piston wings working in the cylinder space between the abutments, said rotor having a hub extension at one end passing through the corresponding cylinder head, the other cylinder head having an inlet chamber, and the corresponding end of the rotor having ports which open into the cylinder space on opposite sides of the piston wings, and a rotatable valve located in the aforesaid inlet chamber and seating on the ported end of the rotor, said valve normally uncovering respectively the end ports of the rotor, and also provided with exhaust passages. 8. A rotary fluid pressure motor comprising a cylinder, heads closing the ends thereof, radial abutments in the cylinder, a rotor in the cylinder and having radial piston wings working in the cylinder space between the abutments, said rotor having a hub extension at one end passing through the corresponding cylinder head, the other cylinder head having an inlet chamber, and the corresponding end of the rotor having ports which open into the cylinder space on opposite sides of the piston wings, and a rotatable valve located in the aforesaid inlet chamber and seating on the ported end of the rotor, said valve normally uncovering respectively the end ports of the rotor, and also provided with exhaust passages, and an operating stem connected to the valve, said stem passing through the rotor and the hub extension and projecting from the latter, and having an exhaust outlet in communication with the exhaust passage of the valve. 9. A rotary fluid pressure motor comprising a cylinder, radial abutments in the cylinder, a rotor in the cylinder and having radial piston wings working in the cylinder space between the abutments, said rotor also having end ports opening into the cylinder space on opposite sides of the pistons, a rotatable valve seating on the ported end of the rotor, said valve normally uncovering respectively the end ports of the rotor, and also provided with exhaust passages, an inlet chamber in which the valve is located, and an operating stem connected to the valve, said stem passing through the center of the rotor and being provided with an exhaust outlet in communication with the exhaust passage of the valve. 10. A rotary fluid pressure motor comprising a cylinder, radial abutments in the cylinder, a rotor in the cylinder and having radial piston wings working in the cylinder space between the abutments, said rotor also having end ports opening into the cylinder space on opposite sides of the piston wings, and a rotatable valve located in the aforesaid inlet chamber and seating on the ported end of the rotor, said valve normally uncovering respectively the end ports of the rotor, and also provided with exhaust passages.

- space between the abutments, said rotor also having end ports opening into the cylinder space on opposite sides of the pistons, a rotatable valve comprising a disk seating on the ported end of the rotor and having chambers on the side which engages said rotor end, from which chambers admission ports extends through the disk to the other side thereof, said ports normally communicating respectively with the end ports of the rotor, said disk on the same side as the chambers also having a central exhaust cavity and passages radiating therefrom, and an inlet chamber in which the valve is located.
11. A rotary fluid pressure motor comprising a cylinder, radial abutments in the cylinder, a rotor in the cylinder and having radial piston wings working in the cylinder space between the abutments, said rotor also having end ports opening into the cylinder space on opposite sides of the pistons, a rotatable valve comprising a disk seating on the ported end of the rotor and having chambers on the side which engages said rotor end, from which chambers admission ports extend through the disk to the other side thereof, said ports normally communicating

cating respectively with the end ports of the rotor, said disk on the same side as the chambers also having a central exhaust cavity and passages radiating therefrom, an inlet chamber in which the valve is located, and an operating stem connected to the valve, said stem passing through the center of the rotor and being provided with an exhaust outlet in communication with the aforesaid exhaust cavity.

12. A rotary fluid pressure motor comprising an inclosing chamber, a rotor having a radial piston wing working in the chamber, and an end recess with ports opening into the chamber on opposite sides of the piston wing, a rotatable valve seating in said recess and normally uncovering both ports, and also provided with an exhaust passage, and an inlet chamber in which the valve is located.

In testimony whereof we affix our signatures in presence of two witnesses.
